CLAIM

The ornamental design for a socket tool, as shown and described.

DESCRIPTION

FIG. 1 is a bottom right side perspective view of a socket tool according to our new design.

FIG. 2 is a top right side perspective view of a socket tool according of FIG. 1.

FIG. 3 is a bottom right side perspective view of a socket tool of FIG. 1.

FIG. 4 is a top plan view of a socket tool of FIG. 1; and, FIG. 5 is a bottom plan view of a socket tool of FIG. 1.

1 Claim, 5 Drawing Sheets
